UNITED STATES PATENT OFFICE

MYER GREEN, OF BROOKLYN, NEW YORK

DESIGN FOR A MIRROR OR GLASS PANELED RADIOCABINET

Application filed October 29, 1930. Serial No. 37,433. Term of patent 7 years.

To all whom it may concern:

Be it known that I, MYER GREEN, a citizen of the United States, residing at Brooklyn, in the county of Kings and State of New York, have invented a new, original, and ornamental Design for Mirror or Glass Paneled Radiocabinet, of which the following is a specification, reference being had to the accompanying drawing, forming part thereof.

Fig. 1 is a perspective view of a radio cabinet having mirror or glass panels arranged at the front and sides, while its rear surface is unornamented.

Fig. 2 is a partial cross sectional view, taken on lines 2—2 of Fig. 1, and showing the arrangement of mirror or glass panels secured to the exterior of the front and sides of the cabinet.

I claim:

The ornamental design for a mirror or glass paneled radio cabinet, as described.

In testimony whereof I herewith affix my signature.

MYER GREEN.
